SCANNING DISK

Application filed December 29, 1928. Serial No. 329,084.

This invention relates to improvements in scanning disks and the method of scanning an object, particularly in television, an object of the invention is to reveal the object by means of that continuous, rhythmic, undulatory movement by which objects are naturally revealed to the eye by reflected light. The objects are: to eliminate the inconvenient restrictions with respect to the area available for use as scanning space as defined by the distances between the open ends of the spirals, to provide means whereby an object may be scanned laterally by intermittent light beams or pencils which maintain perpendicularly a continuous, rhythmic, undulatory movement throughout the period of revolution of the disk; to provide means whereby the total area of the scanning space may be varied with respect to its dimensions; to provide means whereby an object may be scanned with one revolution of the disk a plurality of times, which, mathematically, is unlimited; and to provide a device capable of accomplishing the aforesaid results and purposes.

25 In the drawings, Figure 1 is a surface view of a scanning disk made in accordance with this invention.

Figure 2 is a surface view of another form of scanning disk made in accordance with 30 this invention.

Like numerals of reference indicate corresponding parts in the various figures.

Referring to the drawings, the numeral 10 indicates a circular disk mounted at its central axis 13 on a shaft 13A suitably rotated. The disk 10 is divided into a plurality of equal sectors or radial areas 11 by the radial lines 12. The disk is also divided into a plurality of concentric areal areas 14 by a plurality of concentric circles 15 having their centres at the axis 13 and which intersect the radial lines 12 to form the spaces 17 bounded by contiguous radial lines 12 and contiguous concentric circles 15, respectively. The image 40 to be scanned is represented in dotted lines at 16. Apertures 18 are formed in said disk 10 in such a manner that each aperture occupies one of said spaces 17 and are spaced from each other circumferentially by an equal 45 number of radial spaces 11 and in such a

manner that only one of said apertures will scan or register on the image 16 at a time. The apertures 18 are spaced at varying distances from the central axis in such a manner that they will lie along a line substantially in the form of a spiral bent outwardly towards the circumference of said disk and commencing at a point adjacent to the central axis as at 20, and proceeding to a point more distant therefrom, as at 21, and from this point along a line in the form of a spiral bent away from said circumference and ending an equal distance from the central axis 13 as the point 20.

The apertures are so arranged along said spirals that, as the disk 10 is rotated, successive sections of the image 16 will be scanned by successive apertures 18 along said spiral.

In Figure 1 is shown a system of arranging the apertures 18 in such a manner that said apertures will lie along a line commencing at a point adjacent the central axis as at 20, and proceed to a point more distant therefrom as at 21 and thence back to a point equidistant from said central axis to the original starting point at 20, as at 20A, and spaced circumferentially from said point by a distance equal to the width of the image 16 to be scanned. Thus, with this arrangement of the apertures, the image 16 will be scanned 80 from bottom to top and from top to bottom in one complete revolution of the disk.

In Figure 2, the apertures are so arranged as to fall along a line commencing at a point adjacent to the central axis as at 20 and proceeding to a point more distant therefrom as at 21A, and thence back to a point 20A the same distance from the central axis as the point 20, thence to a point 21B equidistant from the central axis as the point 21A, and thence to a point 20C adjacent to the original starting point 20 and spaced therefrom a distance equal to the width of the image 16 to be scanned and spaced an equal distance from the central axis as said point 20. In this system, the object will be scanned laterally from bottom to top and top to bottom in successive sections twice in one revolution of the disk, in an undulating wave of light pencils or volumes.

The drawings referred to above illustrate two systems. The first, shown in Figure 1, scans the object 16 twice successively, once from bottom to top and again from top to bottom in one revolution of the disk 10. This double movement constitutes one undulation. The term duplex will be hereinafter used to designate this system. The second, Figure 2, scans the object four times, once from bottom to top, again from top to bottom, again from bottom to top and again from top to bottom, on one revolution of the disk, and this quadruple movement constitutes two undulations. The term quadruplex will be hereinafter used to designate this system.

It is to be noted in these systems as shown in Figures 1 and 2, that when the object 16 has been scanned once in consecutive sections from bottom to top, the successive movement begins with the topmost section and not with the one immediately beneath it. This topmost section is therefore scanned twice in succession, thus maintaining its equality with the other sections of the object with respect to the reception of equal light volumes during the period of one undulation. It will be further noted that this movement begins and ends with the scanning of the lowermost section of the object 16. When the revolving disk enters into its second undulatory period, it is necessary that the lowermost section of the object which has just been scanned in completion of the first undulatory period, be scanned again in immediate succession to properly start the second undulation. These essential conditions indicate that means must be provided for scanning the uppermost and lowermost sections of an object twice in immediate succession and this I have achieved by the introduction of what shall hereinafter be designated as loops, as shown at 23. A loop consists of a definite number of radian spaces 11 plus one aperture 18 located in the same arcual area 14 as the aperture to the immediate right or to the immediate left of it.

The spirals with their intermediate loops constitute what I may comprehendingly designate as a closed circuit as differentiated from the open circuits used in other scanning systems. It is solely through the medium of a closed circuit system that undulatory movement can be achieved.

In plotting these systems, I have begun them at the bottom of the scanning area and bent the spirals along which the apertures 18 are arranged outwardly towards the periphery of the disk. The scanning therefore starts from the bottom and continues to the top of this area. They may of course be started at the top of the scanning area, thus bending the spirals inwardly towards the centre of the disk, in which event the scanning movement would be first from top to bottom and then from bottom to top. This would effect a reduction in the size of the

apertures in the greater part of the series, and it is conceivable that this might be desirable.

The scanning disk, which has been divided circumferentially by a plurality of radial lines to form circumferential divisions and has been divided radially by a plurality of concentric circles to form radial divisions, may be conveniently plotted by the following formula, in which

A represents the number of circumferential divisions of the entire disk;

B represents the number of radial divisions included within the scanning area;

C represents the number of circumferential divisions between successive apertures; and

D represents the number of times the scanning area is scanned in one revolution of the disk, and also the number of spirals in the system.

The following equation represents the relationship of the above quantities:

$$A = BCD.$$

It is to be noted that this equation may be solved for C or B as follows:

$$C = \frac{A}{BD}; B = \frac{A}{CD}.$$

By assuming the various constants of the disk, the apertures may be conveniently laid out in accordance with any desired scheme by following the above formula so as to completely scan the image any desired number of times for each revolution of the disk.

I do not limit myself to any designated multiples in scanning methods in this application. Neither do I limit myself to the size or form of the apertures which in the illustrations accompanying this specification and forming a part thereof are designated by spaces bounded on each of their sides by two contiguous radial lines and at top and bottom by the arcs of two concentric circles.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What I claim is:

1. A scanning disk having a plurality of apertures therein arranged in reverse spirals, each of said apertures being bounded by arcs of concentric circles and by radii of the disk.

2. A scanning disk having a plurality of apertures therein arranged in reverse spirals, each of said apertures being bounded by arcs of concentric circles and by radii of the disk, the adjacent apertures at the ends of the two spirals lying at the same distance from the center of said disk.

3. A scanning disk having a plurality of apertures therein, said apertures being arranged in reverse spirals, one of said spirals beginning at the outer edge of an image and ending at the inner edge thereof, the other of said spirals beginning at said inner edge and ending at said outer edge, the adjacent apertures of said spirals being the same radial distance from the center of said disk whereby the edges of said image are scanned twice in succession, each of said apertures being bounded by arcs of concentric circles and by radii of said disk.

4. A scanning disk having a plurality of apertures therein, said apertures being arranged in reverse spirals, one of said spirals beginning at the outer edge of an image and ending at the inner edge thereof, the other of said spirals beginning at said inner edge and ending at said outer edge, the adjacent apertures of said spirals being the same radial distance from the center of said disk whereby the edges of said image are scanned twice in succession, each of said apertures being bounded by arcs of concentric circles and by radii of said disk, the area of said apertures varying directly as the radial distance thereof from the center of said disk.

5. A scanning disk having a plurality of apertures therein, said apertures being arranged in reverse spirals, one of said spirals beginning at the outer edge of an image and ending at the inner edge thereof, the other of said spirals beginning at said inner edge and ending at said outer edge, the adjacent apertures of said spirals being the same radial distance from the center of said disk whereby the edges of said image are scanned twice in succession, each of said apertures being bounded by arcs of concentric circles and by radii of said disk, all of said apertures being of the same radial dimension, said apertures having a circumferential dimension which is directly proportional to the radial distance thereof from the center of said disk.

Signed at the city of Toronto, this 17th day of December, 1928.

ALFRED ORDE TATE.
